UNITED STATES PATENT OFFICE.

WILLIAM S. WHITMAN, OF BANGOR, MAINE, ASSIGNOR TO THE BANGOR FOUNDRY AND MACHINE COMPANY, OF SAME PLACE.

DESIGN FOR A RANGE.

SPECIFICATION forming part of Design No. 16,202, dated August 11, 1885

Application filed February 17, 1885. Term of patent 14 years.

To all whom it may concern:

Be it known that I, WILLIAM S. WHITMAN, a citizen of the United States, residing at Bangor, in the county of Penobscot and State of 5 Maine, have invented and produced a new and original Design for Ranges, of which the following is a specification, reference being had to the accompanying photographic illustration, forming part thereof.

10 The photographic illustration shows a view of the front of my range, and also of one side, which contains the draft-doors and registers. The other side and back of the range are plain.

The general design of the ornamentation 15 consists in the outwardly-swellings doors and panels, having convexly-curved moldings *d* around their outer edges. The inner edges of the moldings are marked by narrow fillets. Spaced centrally in the panel of the oven-door 20 *g* is the name-plate *h*, shaped as a rectangular parallelogram and having a background of waved basket-work, the whole name-plate being in low relief above the panel and surrounded by a convexly-curved molding. In low relief 25 above the panel, above and below the name-plate *h* and at each corner of the panel of the door *g*, is a flabelliform ornament, *i*.

The feed-door *k*, sifting door *k'*, and ash-door *k''* of the range, as well as the door *k'''* of 30 the hot closet *b*, front panel, *m*, of the water-tank *a*, and panel *m'* on the side of the range, are of the same general design of ornamentation and similar to that of the oven-door *g*, already described. These doors *g k k' k'' k'''* and 35 panels *m m'* all swell outwardly, and are surrounded by convexly-curved moldings *d*, terminated on their inner edges by narrow fillets.

Spaced centrally in the aforesaid doors and 40 panels are removable ornamental plates *n*, having a fanciful and partly Egyptian figure upon a background of plain basket-work, and a flabelliform figure, *i*, at each corner, the whole in low relief above the panel and surrounded by a convexly-curved molding. At each corner of the panels *m m'* and the panels of the doors *k k' k'' k'''* is a flabelliform ornament, *i*, in low relief. The doors *k k' k'''* are of the 45 same ornamentation in each. That of the

panels *m m'* is similar, to conform with the shape of the panels. That of the door of the 50 hot closet *b* is similar, and the fanciful Egyptian figure here appears three times upon the plate—twice extended longitudinally and once vertically. The flabelliform figure also appears upon the swell of the legs of the stove. 55

The stove-pipe is incased in a sleeve of lace-work, *c*, carrying the fanciful Egyptian figure used upon the doors and panels nearly in its center, and with the base *o* edged with fillets, having between them the fanciful design *p*, 60 consisting of a flat ring and cross with laterally-projecting arrow-heads. The sleeve *c* has lateral wings *q*, of similar laced design, resting upon similar bases with similar ornamentation, consisting of the flat ring and cross connected with arrow-heads by interchained flat rings of uniformly-diminishing size outwardly from the central ring. The sleeve and wings support the stove-shelf *r*, above which the wings unite and form a lace-work back to the 70 shelf.

What I claim as my invention, and desire to secure by Letters Patent, is—

1. In a design for a range, the door, shaped and ornamented as shown and described, having the rectangular molding *d* and the flabelliform figure *i* in the corners thereof. 75

2. In a design for a range, the door, shaped and ornamented as described and shown, having the rectangular surrounding bead *d* and 80 the central pointed and partially star-shaped Egyptian figure *n*.

3. In a design for a range, the sleeve *c*, having the lace-work composed of a series of concentric circles of different radius and a series 85 of radial bars, as shown and described.

4. In a design for a range, the sleeve *c*, having the lace-work ornamentation, and the base *o*, having the figures *p*, diamond-shaped in outline and composed of interlinked circles and 90 terminal points, as set forth.

Bangor, February 14, 1885.

WILLIAM S. WHITMAN.
